MARTIN H. GERRY, 3D, OF SAN FRANCISCO, AND CLAUDE J. BROOKS, OF REDWOOD CITY, CALIFORNIA, ASSIGNORS TO E. H. EDWARDS CO., OF SAN FRANCISCO, CALIFORNIA, A CORPORATION OF CALIFORNIA

APPARATUS FOR HEAT TREATING WIRE

Application filed May 31, 1928. Serial No. 281,680.

Our invention relates to the process of heat treating wire, and particularly to the "double lead" process of hardening or "patenting" steel wire, and its broad purpose is 5 to provide a method of heat treatment which may be practiced with a maximum economy of fuel and heat treating material, and with a minimum loss of time due to shut-downs.

An object of our invention is to provide a 10 method of using the lead process of heat treatment which obviates the constantly recurring shut-downs for replacing the pans in which the lead is heated.

Another object of our invention is to provide 15 a process which minimizes the wastage of lead, both from direct oxidation and spillage.

Still another object of our invention is to provide 20 a method of treating wire which conserves fuel.

A further object of our invention is to provide 25 a method of treating wire which yields a wire of uniform high quality.

Other objects of our invention are to provide 30 an apparatus suitable for practicing the method of our invention, and one which is not subject to former limitations as to size.

Our invention possesses other objects and 35 valuable features, some of which will be set forth in the following description of our invention which is illustrated in the drawings forming part of the specification. It is to be understood that we do not limit ourselves to the showing made by the said description and drawings, as we may adopt varying forms of 40 our invention within the scope of the claims.

In heat treating wire, and especially in the hardening or "patenting" of steel wire, it is essential that the temperatures to which 45 the material is subjected, and its rates of heating and cooling, be held within narrow limits.

Experience has proved that one of the most 50 satisfactory ways of doing this is to pass the wire through baths of fused material which are maintained at the required temperatures. The material used for the baths may be a salt, such as barium chloride, or a metal having a suitable melting point and a low affinity for the wire. Lead is perhaps the most suit-

able and widely used of these materials, and in the double lead process the wire is first drawn through a bath of lead which is maintained at a temperature of about 1600° F., and is then quenched in a second bath, maintained at about 925° F. The large mass and thermal capacity of the baths prevents slight momentary fluctuations of intensity in the heating flames from developing hard or soft spots in the wire; and the baths also exclude air from contact with the wire during most of the process, and thereby prevent oxidation.

The lead is ordinarily heated in covered cast iron pans, upon which the flames play from beneath. Owing to the high temperature at which the pans must be maintained their oxidation is very rapid, the average life of such a pan being about a week. By substituting cast chrome steel for the cast iron pans this period may be extended to an average of about three weeks, but at the end of this time the furnace must be shut down, the brickwork torn out, and the pan replaced, with a loss of about 48 hours in running time and of a considerable quantity of fuel.

Moreover, there is loss of lead by oxidation from the surface of the bath, and should the pan crack and leakage occur, the spilled lead oxidizes almost instantly and passes off with the flue gases. It is to the suppression of 55 these losses and inconveniences that our invention is directed.

The drawings show a wire treating furnace embodying our invention and adapted to the practice of our method; Fig. 1 being a plan, and Figs. 2 and 3 being sectional views. The planes of section are indicated, respectively, by the lines 2-2 of Figure 1 and 3-3 of Figure 2.

In terms of broad inclusion, our invention 60 comprises the use of a treating bath formed in a refractory hearth and in a substantially closed chamber. The bath is heated by the application of a reducing flame above its surface, means being provided to screen a portion of this surface from the action of the flame. A reducing agent, such as carbon, in the form of coke or charcoal is also preferably floated on the surface of the bath for the further prevention of oxidation. Guides,

conveniently integral with the screening means, direct the wire into and out of the screened portion of the surface of the bath. In the preferred method of operation, a quenching bath is also used, placed as closely as possible to the heating bath, and the fuel is conserved both by making this bath of such dimensions that the heat carried to it by the treated wire is sufficient to maintain it at the proper quenching temperature, and by drawing the wire toward the treating bath through a preheating chamber forming the flue through which the combustion gases are exhausted.

In terms of greater detail, a preferred form of the apparatus of our invention comprises a heating furnace which is supported upon the I beams 6. A heavy iron pan 7 rests upon the I beams, and in this pan, upon a sand cushion 8, is built an inverted arch hearth 9 of fire-brick or other suitable refractory material.

The side walls 10 of the furnace rest directly on the pan 7, the sand cushion lying between them. The arch must be as carefully constructed and keyed as though it were uninverted and loaded in the usual way, as otherwise the buoyancy of the bricks in the exceedingly dense lead bath 11 held by the hearth would immediately bring them to the surface and so destroy the hearth. The end walls 12 and 13 are, like the arch, separated from the pan 7 by the sand cushion. Each end wall is capped by a guide 14, over which the wire 15 which is to be treated bends as it enters or leaves the furnace. These may be of iron or, preferably, of chrome steel.

Stresses due to the expansion of the hearth are transmitted through the cushion to the pan, which is reinforced to support them by transverse I beams 16 held by tension rods 17.

Built over the hearth is a combustion chamber comprising the side walls 10, an arched roof 18, and front and rear end walls 19 and 21, all of a refractory material such as fire-brick. The end walls are not directly over those of the hearth, but are slightly closer together, and between these walls and the end walls of the hearth are openings 22 and 23 for passing the wire. The front opening 22 is as narrow as is conveniently possible. The rear opening 23 passes the discharge gases and is made of adequate size for this purpose. Buckstays 24 give structural stability to the furnace.

The front wall of the furnace is provided with a port through which a burner 26 directs a flame above the upper surface of the bath. A portion of the surface at each end is screened from the flame by the baffles 27 and 28, each of which extends below the surface to serve as a guide for the wire. As in the case of the guides 14, chrome steel appears to be the most satisfactory material for these baffles, altho other materials may be used.

Doors 29 in the side wall give access to the interior of the furnace for inspection or manipulation.

The exhaust gases from the furnace are led through the opening 23 through a pre-heating chamber 31, formed of masonry with steel reinforcements 32, whence the gases pass downward through the flue 33 and so to a stack 34. At the back of the preheating chamber guide rollers 36 and guide pins 37 are provided to direct the various lines of wire through the opening 38 into the chamber. In the top of the chamber near its front end is a manhole 41, beneath which is a wire separator or guide which preferably comprises a plurality of triangular ribs 42 on a flat base 43.

In front of the heating furnace is the quenching bath 44 which is held in a pan 46 having sloping sides. The rear edge of the pan is placed as close to the guide 14 as possible, to minimize the time of transition of the wire between the baths. A masonry combustion chamber 47 having a central wall 48 supports the pan; and a burner 49 is provided on each side of the wall to supply the necessary heat. A flue 50 leads from the combustion chamber to the stack 34.

Above the pan adjustable guides are provided for directing the wire through the bath. These are held by brackets 51, and each comprises a pair of levers 52 secured to a shaft 53 and carrying a roller 54 between their lower ends. A gear sector 56 is fixed to each end of the shaft and meshes with a pinion 57 on a second shaft 58 which may be rotated by the crank 59. It is thus possible to raise the rollers above the surface of the bath for threading the wire beneath them.

An oil line 61 feeds the burners 26 and 49 and passes through the flue 33 for preheating the oil. Suitable valves 62 are of course provided for controlling each burner.

In starting operation, the baths are brought to temperature by means of the burners. The manhole 41 is opened and the wire lines are arranged between the ribs of the separators, and then each line, with an iron plate secured to its end, is thrust into the bath and under the baffle 28, the plate floating to the top of the molten bath. Other wires, similarly floated, are inserted under the guide 27 from the other end of the furnace and the wires from the two ends are secured together by workmen operating through the doors 29. The wires are then pulled through the bath and threaded under the guides of the quenching bath, and all is ready for operation.

The burner 26 is adjusted to give a flame which will maintain a reducing atmosphere over the bath and in the preheating chamber and thus prevent oxidation of the bath and of the wire. A reducing agent, preferably carbon in the form of charcoal or coke, is floated

on the surface of the bath for the further prevention of oxidation.

The usual form of winding mechanism is used to draw the wire smoothly and uniformly through the preheating chamber and the successive baths. After the operation is started, the flames from the burners 49 may be reduced or even extinguished completely, the quenching bath being maintained at the proper temperature by the heat carried to it by the wire.

In a furnace such as the one described, shutdowns are practically eliminated. The circulation of air between the I beams 6 under the furnace keeps the iron pan 7 sufficiently cool so that little if any deterioration takes place, and rebuilding of the furnace for replacing the cast pans of usual practice is of course eliminated. The temperature of the quenching bath is not sufficiently high to cause rapid deterioration of the pan or oxidation of the lead.

We claim:

1. In a wire treating furnace, a hearth composed of refractory earth material for containing a bath of molten lead, means restraining the hearth against flotation, means for applying flame on the bath, means for guiding a wire through the bath, and means for confining the flame to a central portion of the bath to avoid burning the wire as it enters and leaves the bath.

2. In a wire treating furnace, a hearth comprising an inverted arch of refractory earth material, means for supporting the arch, means for applying flame over the hearth, means for confining the flame to a central portion of the hearth, and means for passing wire into and out of the furnace externally to said central portion.

3. In a wire treating furnace, a substantially closed chamber, a hearth composed of refractory earth material in said chamber for holding a treating bath, means for applying a flame on said bath; means for guiding the wire into, through, and out of said bath; means for screening the wire from the direct action of the flame prior to its entrance into the bath, means for screening the wire from the direct action of the flame when it leaves said bath; a flue associated with said chamber, and means for guiding the wire through a portion of said flue prior to its entrance into the bath to effect preheating.

4. In a wire treating furnace, a substantially closed chamber, a hearth composed of refractory earth material in said chamber for holding a treating bath, means for applying a flame on said bath; baffles adjacent opposed ends of the chamber for guiding the wire into and through said bath, and for screening the wire from the direct action of the flame prior to its entrance into, and when it leaves said bath; a flue associated with said chamber, and means for guiding the wire through a portion

of said flue prior to its entrance into the bath to effect pre-heating.

5. In a wire treating furnace a hearth of refractory material for containing a bath of molten lead through which the wire may be drawn, said hearth comprising a plurality of bricks laid to form an inverted arch, means for directing the wire into said bath, means for directing the wire out of said bath, means for applying a flame on said bath, means for screening the portion of the wire between the point at which it enters the furnace and enters the bath, from the direct action of the flame, and means for screening the portion of the wire between the point at which it leaves the bath and leaves the furnace from the direct action of the flame.

In testimony whereof, we have hereunto set our hands.
